UNITED STATES PATENT OFFICE.

GIUSEPPE MONTRONI, OF HOBOKEN, NEW JERSEY, ASSIGNOR TO THE ART HAND-BAG FRAME CO., OF NEW YORK, N. Y., A COPARTNERSHIP.

DESIGN FOR A HAND-BAG FRAME.

53,275.

Specification for Design.

Patented May 6, 1919.

Application filed February 11, 1919. Serial No. 276,445. Term of patent 3½ years.

To all whom it may concern:

Be it known that I, GIUSEPPE MONTRONI, a subject of the King of Italy, residing at Hoboken, in the county of Hudson and State of New Jersey, have invented a new, original, and ornamental Design for a Hand-Bag Frame, of which the following is a specification, reference being had to the accompanying drawing forming part thereof.

The figure is a front view of a hand-bag frame with the design applied thereto.

I claim:

The ornamental design for a hand-bag frame substantially as shown.

GIUSEPPE MONTRONI.
